UNITED STATES PATENT OFFICE.

JULIUS HOHAGEN, OF VELBERT, GERMANY.

LOCK.

SPECIFICATION forming part of Letters Patent No. 710,692, dated October 7, 1902.

Application filed November 30, 1901. Serial No. 84,184. (No model.)

To all whom it may concern:

Be it known that I, JULIUS HOHAGEN, a citizen of the German Empire, and a resident of Velbert, Rhenish Prussia, Germany, have invented certain new and useful Improvements in Door-Locks, of which the following is a specification.

This invention relates to an improved latch-lock, and more particularly to improved means for operating the latch in a simple and convenient manner.

In the accompanying drawings, Figure 1 is a front view of my improved latch-lock. Fig. 2 is a section, partly in side view, on line A—B, Fig. 1. Fig. 3 is a section on line C—D, Fig. 2. Fig. 4 is a detail showing the position of the parts when the latch is closed, and Fig. 5 a similar detail showing the position of the parts when the latch is open.

The letter *a* represents a concave semi-spherical knob having a tubular stem *c*. Within the bore *l* of this stem is free to slide a push-pin *s*, the button *k* of which is received within the hollow of the knob *a*. The inner end of pin *s* engages one end of a lever *h*, which is pivoted within stem *c*, and the other end of which engages a perforation *o* of the bolt *o'*.

In use the knob *a* is grasped by two fingers and the thumb is pressed upon the button *k*,

so as to swing the lever *h* in the direction of the arrow, Fig. 4, and open the latch. Upon releasing the pressure the latch will be closed by its spring *o'*, which will also return the lever *h* and pin *s* to their normal position. 35

The inner threaded ends of the stems *c* are engaged by nuts *m*, which are connected by bolts *q*. Projections *n* of stem *c* enter corresponding perforations of the lock-plates *n'* and hold the knobs *a* against turning. The 40 nuts *m* are concealed by face-plates *r*, that may be adjusted upon the stems *c* in accordance with the thickness of the door.

What I claim is—

A latch-lock composed of a pair of tubular 45 stems having threaded sections and projections beyond said threaded sections, push-pins movable within the stems, levers engaged by the push-pins, a latch operatively connected to the levers, perforated lock-plates 50 engaging the stem projections, nuts engaging the stem-threads, and bolts connecting the nuts, substantially as specified.

Signed by me at Dusseldorf, Germany, this 7th day of November, 1901.

JULIUS HOHAGEN.
